UNITED STATES PATENT OFFICE.

FRIEDRICH WEBEL, OF WEST HOBOKEN, NEW JERSEY.

STAMPING-MACHINE.

1,127,704.

Specification of Letters Patent.

Patented Feb. 9, 1915.

Application filed June 1, 1914. Serial No. 842,009.

To all whom it may concern:

Be it known that I, FRIEDRICH WEBEL, a subject of the Emperor of Austria-Hungary, and a resident of West Hoboken, in the county of Hudson and State of New Jersey, have invented new and useful Improvements in Stamping-Machines, of which the following is a specification.

This invention relates to stamping machines in which a series of dies or punches are carried by a rotatable die head to stamp or punch a character or characters upon a plate, such as a name plate, a key check and the like. In this type of stamping machine a character dial is rotatable with the die head to indicate the proper positioning of the dies. However, the rotating or whirling around of the character dial tends to confuse the operator with the result that a wrong character is stamped or punched upon the plate.

It is the principal object of the present invention to overcome the above disadvantage of the confusion arising from the rotation of the character dial, and for which purpose I provide a fixed character dial, preferably in superposed relation to the die head, and connect to the die head to rotate therewith an indicator or pointer to indicate on the dial the proper positioning of the die head.

Further objects of the invention relate to improved means to slidably support the dies or punches by the die head, to means to actuate the dies, and to adjustable means to feed or advance the plate upon which the characters are to be punched a predetermined distance upon each operation of the die actuating means.

In the drawings accompanying and forming a part of this specification, Figure 1 is a plan view of a stamping machine illustrating an embodiment of my invention. Fig. 2 is a side elevation, partly in section. Fig. 3 is an enlarged sectional detail view of die mechanism. Fig. 4 is an enlarged fragmentary perspective view to illustrate the means to regulate the feeding or advancing of the plate upon which a character is to be stamped. Fig. 5 is a fragmentary sectional view in perspective of the die head. Fig. 6 is a perspective view of a portion of the spring to maintain the dies in the die head. Fig. 7 is a perspective view of the preferred form of die. Fig. 8 is a sectional view of a portion of a modified form of die head.

Fig. 9 is a perspective view of a modified form of die to be utilized in connection with the construction of die head shown in Fig. 8. Fig. 10 is an enlarged side elevation, partly in section, showing a modified form of character dial mounting; and Fig. 11 is a similar view to Fig. 10 showing a still further form of mounting the character dial and the connecting of the pointer to the die head.

Similar characters of reference designate like parts throughout the different views of the drawings.

In the embodiment of my invention illustrated in drawings the operative mechanism is mounted upon a base or framework (designated in a general way by F). A circular die carrying head 12 is fixed adjacent one end of said base to a stud shaft 13 rotatably mounted in the base, said head having a central boss to rest upon the base and a collar 14 fixed to the shaft on the opposite side of the base preventing axial movement of the shaft.

The head 12 is preferably circular in shape and has a lateral annular flange 15 provided with a series of radial recesses or slots 16, the side walls of which recesses incline from the top to the bottom for a purpose to be hereinafter described. The periphery of the head also has a series of slideways or slots 17 extending in a direction axially with the head, and said slideways correspond to and are in line with the recesses 16. Slidably mounted in the slideways are dies or punches 18 having a character at one end which is at the bottom of the head. These punches correspond in form to the shape of the slideways and are maintained in the slideways so that the upper ends are flush with the bottom of the recesses 16 by a spring or springs, in the present instance consisting of a resilient circular comb 19, the teeth of which comb correspond with the number of dies. This comb is fixed to the bottom of the die head so that the teeth are in line with but come below the slideways 17 and are of such length that they will project beyond the walls of such slideways and adapted to engage in a notch in the punches, as clearly shown in Fig. 3. To prevent radial or lateral displacement of the dies I provide an annular band 23, said band having a knurled portion (as shown in Fig. 2) to facilitate the adjusting of the die head or carrier.

Fixed to a lug 20 projecting up from the base (Fig. 2) is a character dial 21 so that it will be superposed to the head 12; the dial having a central opening through which the 5 shaft 13 projects and to which projecting end of the shaft a pointer or indicator 22 is fixed to indicate on the dial the proper positioning of the head 12.

A plate or check 24, in the present instance circular in shape, upon which to 10 punch a character or characters, is supported in a recessed portion of a disk 25, said disk being located in a recess in the top of the base so that the disk with the plate 15 will be flush with the top of the base and come below the die carrier and dies and permit of the punching of the characters adjacent the periphery of the plate. The plate is maintained on the support 25 by a 20 resilient finger 27, and to prevent rotative movement of the plate relative to the support a pin 28 in the support projecting above the surface thereof engages in an opening provided in the plate 24.

25 To impart sliding movement to a die or punch to stamp a character on the plate 24 I provide a rocker arm 29 pivotally supported between a pair of lugs 30' projecting up from the base, a plunger 30 being carried 30 by said arm and passing through an opening in the dial 21, the end of which plunger is beveled to correspond with the recesses 16, whereby the pressure will be centralized on the end of the die or punch. Movement is 35 imparted to the arm 29 and thereby through the plunger to the dies by a hand lever 31 also pivotally supported between the lugs 30' and having a fulcrum connection with the arm 29, as shown at 32' in Fig. 2. When 40 the lever 31 is depressed a die is forced downward against the plate 24 against the tension of the teeth of the comb 19, and when pressure on the lever is released it is returned to initial position by a spring 32, 45 the tension of the comb finger returning the die to initial position. The downward movement of the lever 31 is limited by a stop in the form of a set screw 33.

To intermittently feed or advance the 50 plate support 25 and plate 24 a predetermined distance to permit of stamping the characters successively upon the plate I secure to the stud 26 below the base F a ratchet wheel 34. This ratchet wheel and 55 thereby the plate carrier 25 is rotated by a spring influenced pawl 35 after each depression of the lever 31 and a character has been stamped upon the plate 24. For this purpose I fix to the lever 31 a cam 36 which 60 is adapted to engage with a friction roller 37 on an arm 38 fixed to a pin or stud 39 rotatably mounted in the base. Fixed to the end of the stud 39 below the base is a bell crank lever 40 upon one arm of which 65 the pawl 35 is pivotally supported. As the

lever 31 is depressed and the cam 36 engages with and throws the arm in the direction of the arrow (Fig. 1) it throws the bell crank lever in the direction of the arrow causing the pawl to ride over the teeth of the ratchet, 70 and when the lever 31 is returned to initial position by the spring the spring 41 connected to the other arm of the bell crank lever will return the latter and cause it to abut against a stop 42 carrying with it the 75 pawl which is caused to engage with the teeth of the ratchet and rotate the latter.

To regulate the feed or adjustment of the plate carrier 25 the stop 42 is in the form of a rotatably adjustable cam fixed to the lower 80 end of a pin 43 rotatably mounted in the base, a spring detent 44 being fixed to the upper end of the pin 43 which is adapted to engage in either one of a series of notches in a segment 45 projecting up from the base, 85 the detent being provided with a finger-piece to facilitate the adjustment of the same and the cam. It will be obvious from Fig. 4 of the drawings that by adjusting the detent to the left the cam will project 90 farther into the path of the lever 40 and limit the movement thereof, and vice versa, and thereby through the pawl 35 limiting the rotative adjustment of the ratchet wheel and plate carrier 25. 95

In Fig. 9 I have shown a modified form of die 18' which is circular in form in cross section. When this type of die is utilized instead of providing the die head with the slideways in the periphery, said die head is 100 provided with a series of circular openings adjacent the periphery, (as shown in Fig. 8,) in which the dies 18' slidably engage and is retained against sliding movement by the resilient comb 19 the same as when the dies 18 are utilized. In this construction it is not necessary to provide the band 23 nor the radial recesses 16. However, the die head has a knurled portion to facilitate the adjustment of the same. The ends of the dies 105 18' are provided with a recess 46 the side walls of which incline from the top to the bottom to correspond with the shape of the plungers 30 and thereby centering the pressures on the die. 110

In the construction shown in Fig. 10 the stud shaft 13 is fixed in the base and the die head is rotatable thereon, the dial 21' being in the form of an annular band with characters thereon extending around the die 120 head and secured to the base, the pointer 22 to indicate the positioning of the die head being secured to the head and having a portion to project over the annular dial 21'. To prevent the removal of the dies there is 125 fixed to the top of the stud 13 a plate 47 having openings adjacent the periphery and in line with the dies to guide the plungers 30.

In the construction shown in Fig. 11 the stud 13 is also fixed and the die head is ro- 130

tatable thereon and the character dial 21 is fixed to the top of the stud, the pointer or indicator being fixed to the side of the die head and having a portion to extend over the dial.

5 Variations may be resorted to within the scope of my invention.

Having thus described my invention, I claim:

- 10 1. In a stamping machine, the combination of a fixed character dial; a rotatable head having means to indicate on the dial the positioning of the head; a series of dies slidably carried by the head; a lever to impart sliding movement to the dies; a rotatable support for a plate upon which the characters are to be stamped; a ratchet wheel connected to said support; and a pawl actuated by the lever when a die is actuated to 15 rotate the ratchet wheel and the connected plate support a predetermined distance.

- 20 2. In a stamping machine of the character specified, the combination of a rotatable head having means to indicate the positioning thereof; a series of dies slidably carried by the head; a support for a plate upon which characters are to be stamped; a rocker connected at one end to the dies to impart sliding movement thereto; and a lever connected to the other end of the rocker to actuate the latter.

- 25 3. In a stamping machine, the combination of a fixed dial; a rotatable head having means to indicate on the dial the positioning of the head; a series of dies slidably carried by the head; a lever to impart sliding movement to the dies; a rotatable disk to support a plate upon which a character is to be stamped; a spring finger to maintain the plate on the disk; and pawl and ratchet mechanism connected to said disk and actuated by the lever when a character is stamped upon the plate to advance the plate support and plate a predetermined distance.

- 40 4. In a stamping machine, the combination of a fixed dial; a rotatable head having means to indicate on the dial the positioning of the head; a series of dies slidably carried by the head; a lever to impart sliding movement to the dies; a rotatable disk to support a plate upon which a character is to be stamped; a spring finger to maintain the plate on the disk; pawl and ratchet mechanism connected to said disk and actuated by the lever when a character is stamped upon the plate to advance the plate support and plate a predetermined distance; and means to limit the advancing movement of the plate support.

- 45 5. In a stamping machine, the combination of a fixed dial; a rotatable head having means to indicate on the dial the positioning of the head; a series of dies slidably carried by the head; a lever to impart sliding movement to the dies; a rotatable disk

to support a plate upon which a character is to be stamped; a ratchet wheel connected to said support; a bell crank lever; a spring influenced pawl to coöperate with the ratchet wheel carried by one arm of the lever; a cam connected to the die actuating lever; an arm connected to the bell crank lever engaged by the actuating lever arm cam to actuate the pawl and ratchet wheel to rotate said wheel and connected disk a predetermined distance upon the actuation of a die; and a spring to return the bell crank lever and arm to initial position.

6. In a stamping machine, the combination of a fixed dial; a rotatable head having means to indicate on the dial the positioning of the head; a series of dies slidably carried by the head; a lever to impart sliding movement to the dies; a rotatable disk to support a plate upon which a character is to be stamped; a ratchet wheel connected to said support; a bell crank lever; a spring influenced pawl to coöperate with the ratchet wheel carried by one arm of the bell crank lever; a cam connected to the die actuating lever; an arm connected to the bell crank lever engaged by the lever cam to actuate the pawl and ratchet wheel to rotate said wheel and connected disk a predetermined distance upon the actuation of a die; a spring to return the bell crank lever and connected arm to initial position; and adjustable means engaged by the bell crank lever to limit the movement thereof and thereby the movement of the ratchet wheel and connected plate carrying disk.

7. In a stamping machine, the combination of a fixed dial; a rotatable head having means to indicate on the dial the positioning of the head; a series of dies slidably carried by the head; a lever to impart sliding movement to the dies; a rotatable disk to support a plate upon which a character is to be stamped; a ratchet wheel connected to said support; a bell crank lever; a spring influenced pawl to coöperate with the ratchet wheel carried by one arm of the bell crank lever; a cam connected to the die actuating lever; an arm connected to the bell crank lever engaged by the lever cam to actuate the pawl and ratchet wheel to rotate said wheel and connected disk a predetermined distance upon the actuation of a die; a spring to return the bell crank lever and connected arm to initial position; and adjustable means engaged by the bell crank lever to limit the movement thereof and thereby the movement of the ratchet wheel and connected plate carrying disk, comprising a cam, a detent connected to the cam, and a notched segment in any notch of which segment the detent is adapted to engage to lock the cam in adjusted position.

8. In a stamping machine of the character specified, the combination of a rotatable

head having means to indicate the positioning thereof; a series of dies slidably carried by the head; a rocker to impart movement to the dies; a lever to actuate the rocker; a rotatable support for a plate upon which characters are to be stamped; pawl and ratchet mechanism to rotate the plate support; means connected to the lever to actuate the pawl and ratchet mechanism and

thereby rotate the plate support a predetermined distance upon the actuation of a die; and adjustable means to limit the movement of the ratchet and connected plate carrier. 10
